UNITED STATES PATENT OFFICE.

FREDERICK W. COLE, OF NEWTON HIGHLANDS, MASSACHUSETTS, ASSIGNOR TO GAME WELL FIRE ALARM TELEGRAPH COMPANY, OF NEW YORK, N. Y., A CORPORATION OF NEW YORK.

SUCCESSIONAL NON-INTERFERENCE SIGNAL-BOX.

1,244,587.

Specification of Letters Patent. Patented Oct. 30, 1917.

Application filed November 2, 1915. Serial No. 59,820.

To all whom it may concern:

Be it known that I, FREDERICK W. COLE, a citizen of the United States, residing at Newton Highlands, in the county of Middlesex and State of Massachusetts, have invented an Improvement in Successive Non-Interference Signal-Boxes, of which the following is a specification.

This invention relates to fire-alarm telegraph signal-boxes, and particularly to that type commonly known as successive non-interference signal-boxes. The ordinary box of this type, when pulled, is arranged to send a predetermined number of rounds of its signal, say four rounds. In case another signal is being sent over the line, or there is trouble on the line, these rounds instead of being sent immediately upon pulling the box, will be delayed for a short or a long period of time depending upon the conditions which caused the delay. There comes a time after a box has been pulled that the transmission of its signal is absolutely useless, its reception being too late for the call of the fire apparatus, and in fact it had much better not then be sent for the reason that it might cause delay in responding to some other signal.

The particular broad characteristic feature of the box embodying this invention is its capability of sending its signal promptly, when the box is pulled, and if for any reason its signal is delayed, then for sending it promptly upon the cessation of the conditions which caused its delay but only within a reasonable length of time, and restoring the component parts to normal as soon as it has sent its signal or at the expiration of the period of time which is allotted for the sending of the signal.

While my invention is of a broad character, and I do not wish to limit it to any particular structure, yet herein the abnormal extension of time within which the signal may be properly sent is acquired by delaying the action of the stopping-means for the signaling-train, in case another signal is being sent over the line, or there is trouble on the line, whereupon the signaling-train is permitted to continue its operation, but cannot send its signal, such delay being for a period of time which varies according to the conditions existing which caused the delay, but in no event will it be longer than a predeter-

mined period of time, which is allotted during which a signal may be sent, and at the expiration of which period of time the stopping-means will operate to stop the train in any event and the component parts of the box will then be restored to normal preparatory to being again pulled. The delaying-means for the stopping-means by which the train is permitted to continue running, but only for a predetermined period of time, may consist of means for disconnecting the stopping-means from the signaling-train, which is operable to thereafter connect the same therewith, thereby to delay the stopping of the train, and subsequently to connect the same with the train, after which it will operate to stop the train when the train has run long enough to send the predetermined number of rounds which it is designed to send.

Disconnection of the stopping-means from the signaling-train may be controlled by the armature of the non-interference magnet, which is the element responsive to another signal being sent from another box or to trouble on the line, and the subsequent connection of the stopping-means with the train consists of means adapted to be operated or controlled by the train in running. Connection of the stopping-means with the train, after it has been disconnected therefrom, will be attempted repeatedly at regular times, as for instance, at the end of each round of the signal during the time allotted for the box to run, and such attempts will be controlled by the train in running, and when made will operate to stop the train after a predetermined number of rounds of the signal have been correctly transmitted or the train has run for a corresponding period of time.

Of course, it will be understood that in case there is no other signal being sent over the line or there is no trouble on the line the stopping-means will not be disconnected from the train and will operate to stop the train when the predetermined number of rounds of the signal have been sent.

By providing for connecting the stopping-means with the train after it has been disconnected therefrom, at regular intervals, as at the end of each round of the signal, will many times result in delaying the sending of the delayed signal only for a short

period of time, which is a great advantage, as it is obvious the sooner a signal is sent after the box has been pulled the better. The time allotted for the signaling-train 5 to run after it has been pulled and has operated to delay the sending of its signal, is herein controlled by a counting-device adapted to be operated by the train in running, being moved at the end of each round 10 of the signal, and when a predetermined number of rounds have been counted off, so to speak, it operates to prevent the armature from further controlling the connection of the stopping-means with the signaling-train, which means is then driven by the train, in regular manner, for a predetermined number 15 of rounds whereupon it operates to stop the train whether the delayed signal is sent or not. The counting-device is adapted to be returned to its normal position by a spring 20 and is released to do so by the stopping-means, thus providing for the return to normal of the counting-device whenever the train is stopped. Thus in accordance with 25 this invention, as illustrated in the embodiment here shown, the disconnecting means for the stopping-means is controlled by the non-interference magnet to disconnect said stopping-means from the signaling-train; 30 and connection of the stopping-means, with the signaling-train, after it has been disconnected therefrom, is attempted at the end of each round of the signal by means controlled by the train in running, and connection 35 of the stopping-means with the signaling-train after it has been disconnected therefrom is maintained in any event at the end of a predetermined number of rounds of the signal by the counting-device which is 40 adapted to be operated by the signaling-train in running to maintain such connection, and is adapted to be released by the stopping-means when acting to stop the train to return to normal.

45 Figure 1 is a front elevation of a successive non-interference signal-box embodying this invention, its component parts being in their normal position of rest.

Fig. 2 is a similar view many of the parts 50 being omitted to expose those in rear of them.

Fig. 3 is a side elevation of the signal-box shown in Fig. 1.

Fig. 4 is a vertical sectional detail of a 55 portion of the box.

Figs. 5 to 9 are fragmentary details of certain associated parts in the different positions they will occupy during the running of the train and under different conditions 60 as will be hereinafter referred to.

The winding-shaft 1 has attached to it the inner end of the main-spring 2, and the outer end of said spring is attached to a fixed stud 3. A toothed-gear 4 secured to 65 said winding-shaft, engages a pinion 5,

mounted to rotate on the stud 3. A stop-member is secured to said pinion or otherwise arranged to rotate with it, which member is here shown as a disk 6 having a projection 7. A pin 8 projects laterally from the face of the toothed-gear 4, and, as said winding-shaft rotates, passes through an orbit, and the projection 7 is arranged to enter the orbital path of said pin upon each revolution of the pinion, and is adapted to be engaged by said pin to limit the winding-motion of the shaft when the spring has been wound, thus to obviate winding the spring overtight. The relative number of teeth on the toothed-gear 4 and pinion 5 are such as to permit the toothed-gear to make several rotations before its pin encounters the projection 7, notwithstanding said projection passes through the orbital path of the pin during each of these rotations. The shaft is wound by turning it counter-clockwise and is rotated by the main spring in a clockwise direction.

There is also mounted on the winding-shaft a spur-gear 10, which is adapted to be driven by the shaft, being connected therewith in any usual manner, as by a pawl 12, arranged on the gear 10, which engages a ratchet-wheel 13 secured to the shaft, so that the energy of the spring may be imparted to said gear. Said gear 10 engages a pinion 14, see Fig. 4 and dotted lines Fig. 2, secured to a shaft 15, to which the box-number signal-wheel 16 is secured. A spur-gear 20 is secured to or arranged to 95 rotate with the signal-wheel shaft, it being here shown as mounted upon and secured to the hub of the pinion 14, and said gear 20 engages a pinion 21, secured to a shaft 22, to which the escapement-wheel 23 is secured, 100 said wheel 23 being engaged by a pallet 24, secured to a pallet-shaft 25, bearing a fan 26. Stripped of associated elements, to be hereinafter described, this train of gearing serves as and constitutes the signaling-train. 105

This signaling-train is adapted to be held at rest against the energy of its actuating-spring by stopping-means adapted to be controlled by the box-pull to start the train, and to be operated by the train in running 110 to stop the train. Furthermore, the stopping-means is adapted to be disconnected from the train, to permit the train to run independently thereof, in case the signal is delayed. The stopping-means here shown 115 consists of a disk 36, having a single notch 37, which receives the end-portion or tooth 38 of a locking lever 39, which is secured to a pivot-shaft 40, said notched disk, which serves as the stop-wheel, being loosely 120 mounted, for convenience, on the winding-shaft 1. Said notched disk is arranged to be driven by the signaling-train by means whereby it will make one rotation to several rotations, say four, of the signal-wheel, 125 130

so that in the normal running of the train, several rounds of the signal, say four rounds, will be sent, at which time the notch of the disk arrives in position for reengagement of the locking-member, whereupon the train will be stopped. To thus rotate the notched disk or stop-wheel, as here shown, a spur-gear 35 is rigidly secured to it, which is engaged by a pinion 34, arranged for convenience on the signal-wheel shaft 15, and adapted for connection with the train.

Said pinion 34 is loosely supported on said shaft 15, and on its hub a disk 33 is rigidly secured, having pivoted on its face, at 32, a dog 31, one end of which has an engaging-portion arranged to engage and disengage a pin 30, which projects laterally from one of the train-wheels, as 20, and the other end of which forms an extension or tail 72, which may extend outward beyond the edge of the disk, see Fig. 2, or may be otherwise arranged for engagement with means to cause it to be moved on its pivot. By means of the pin 30 and dog 31, the stopping-means is adapted to be connected with and disconnected from the train. When the dog is in engagement with the pin, the stopping-means is connected with the train, and when moved on its pivot to disengage the pin, the stopping-means is disconnected therefrom. When the locking-lever 39 engages the notch in the disk or stop-wheel 36, and the dog 31 engages the pin 30, the signaling-train is held at rest through the gear 35, pinion 34, disk 33, dog 31, pin 30, and train-wheel 20; and when said locking-lever disengages said notch the signaling-train is permitted to run; and when the dog 31 is moved out of the path of movement of the pin 30, the signaling-train is permitted to run and the stopping-means, including the stop-wheel, is permitted to remain at rest.

The box-pull 41, shown as a pivoted lever, is arranged beneath the locking-member 39, by which said member may be lifted against the tension of its return-spring 42, to disengage the notched disk 36, and thereby release the signaling-train.

The signal-key 45 is arranged to control the make and break of a pair of contact-pens 46, 47, by coöperating with the signal-wheel 16, it having a projection 51, arranged for engagement with the toothed edge-portion of the signal-wheel for the accomplishment of this result. It is pivoted at 48, and its movements to and fro are limited by a pin 49, which is extended laterally from it and enters a hole 50 in the frame, which hole is made larger than the pin. It also has a pin 52, arranged for engagement with a prop 53, by which it is held in its closed circuit position, but which, when said prop is lifted, will pass beneath the prop, so as to act to hold the

prop in elevated position while said key is in its open position. The upper end-portion of the key is arranged for coöperation with a pin 54, on the box-controller, in such manner that each can at times control the other, as will be observed. Its lower end-portion has an extension 55 which is arranged to be engaged by a pin 56 on the locking-member 39, by which it is restored to normal or closed position when the locking-member enters the notch of the stop-wheel.

The prop 53 is pivoted at one end, as at 58, adjacent the signal-wheel, and is spring pressed, and has two projections 60 and 61, at its free end. The projection 60 is adapted for engagement with the pin 52 on the signal-key, so that said key may be held at times by the prop, or the prop by the key. The projection 61 is adapted for engagement with a cam 63, which is arranged on or rotatable with the signal-wheel. This cam extends entirely around or is co-extensive with the signal-wheel and might be made as a flange on the wheel; and a portion thereof, which corresponds with the period between the end of one round and the beginning of the next round of the signal, is cut away, or in lieu thereof a void may be provided. Along the cut-away portion of the cam the prop is permitted at times to move into its lowermost position, see Fig. 1, in which position its projection 60, engages or passes beneath the pin 52 on the signal-key to act thereafter to hold or prop said key with its contact-pens in closed position.

The remaining portion of the cam acts to lift and hold the prop high enough for its projection 60 to move into a plane above the pin 52, see Fig. 5, so as to admit of said pin passing beneath it. When the prop is thus lifted by the cam, the signal-key is free to move into the interdental spaces of the signal-wheel, unless otherwise held, and when so moved, see Fig. 6, its pin 52 will pass beneath the projection 60 on the prop, and will act to hold said prop in elevated position, so as to prevent it from again falling into its cut-away portion.

When the box is at rest, the projection 61 on the prop will be disposed intermediate the length of the cut-away portion of the cam, and the prop will then be in its lowermost position in the notch, and its projection 60 will be in propping position for the key which is then held in closed position by the locking lever, see Fig. 1. Upon pulling the box and starting the train, the key will temporarily be held from opening while the notch in the cam is passing and the signal-wheel will rotate and when its first tooth reaches the key the cam will soon lift the prop into the position shown in Fig. 5, thereby disengaging the signal-key, and the

signal-key will then engage the first tooth of the signal-wheel, and thereafter fall into the first interdental space, as shown in Fig. 6, whereupon the contact-pens are opened. 5 With the parts in this position, the first break of the circuit for a signal is produced.

As the signal-wheel continues to rotate, and the signal-key repeatedly enters the 10 interdental spaces thereof the pin 52 will repeatedly pass beneath the prop, for the reason that the prop is held in elevated position by the cam, during the rotation of the signal-wheel, and until the cut-away portion arrives opposite the projection 61 thereof. The cut-away portion of the cam is arranged opposite the long interdental space of the signal-wheel, which occurs between and is designed to differentiate the 15 rounds of the signal. The signal-key will be in its open position between the rounds of the signal, and its pin 52 will then be disposed beneath the prop at the time said prop arrives at the cut-away portion, so that the 20 prop will be held in elevated position during the passing of said cut-away portion by the signal-key, unless it should so happen that the signal-key is held in or restored to closed position by other means, as, for instance, by abnormal position of the box 25 controller or the return movement of the locking-member to normal at the completion of an alarm.

The time consumed in moving the signal-wheel from the position shown in Fig. 1 to the 30 position shown in Fig. 5, to disengage the signal-key, is of longer duration than the longest closure in any signal, and it is during this time that the box is placed 35 under the control of the circuit, as will be described, so that if another signal is being sent over the line, or there is trouble on the line, the signal which is about to be sent will be delayed.

45 The delay of the signal is controlled by the non-interference magnet 65, the armature 66 of which is arranged on the controlling-lever 67, herein termed the box-controller, which is pivoted at 68.

50 A pin 54 of cylindrical formation and slabbed off on its underside is extended laterally from the box-controller and normally occupies a plane above and at one side of the upper end of the signal-key, that is to say, these are the relative positions when the armature is in its attracted position and the signal-key is in its closed position. When so arranged both are free to respond. In case the signal-key responds while the 55 armature is in its attracted position, its end-portion moves to a position beneath the pin 54, and will act to hold the armature in its attracted position, so that while the signal-key is in open position the armature will be 60 held in its attracted position. Thus during

the normal operation of the box, in case the line is clear, the armature will be repeatedly held in its attracted position, when the circuit is opened by the signal-key. In case the armature is or should be retracted 70 while the signal-key is in its closed position then said pin 54 will be moved to one side of the signal-key and into its path of movement, and in such position will act to prop and thereby hold said key in its closed position, until the armature is again moved into its attracted position, so that no signal can then be sent by said key, notwithstanding the train is running.

In case another signal is being sent over 80 the line, or there is trouble on the line, the non-interference magnet will respond to such condition during the prolonged period of time which follows the pulling of the box and precedes the first opening of the signal-key, and will move the pin 54 into position to hold the signal-key in its closed position, notwithstanding the signaling-train is running and the prop has been properly moved into its disengaging position, thus 85 the sending of the signal will be delayed.

After the armature is moved into its retracted position for the purpose of causing the signal to be delayed the stopping-means will be disconnected from the signaling- 95 train.

As a means for accomplishing this result, as here shown, a pin 70 is extended laterally from a projection 71 on the box-controller, which, when the armature is retracted, is moved into the path of movement of the tail 72 of the dog 31, so that upon engagement therewith said dog will be moved to disengage the pin 30, as shown in Fig. 8. Said pin 30 then continues its orbital movement with the train-wheel 20, and the train continues to run, but the stopping-means is disconnected from the train and remains at rest, and, as the box-controller when thus retracted also engages and 100 holds the signal-key in its closed position, the signal will likewise be delayed.

An attempt to send the delayed signal is subsequently made at each revolution of the signal-wheel, by mechanically restoring or 115 placing the armature in its attracted position and leaving it under control of its magnet at such times, and before a round could be started. For the accomplishment of this result a pin 75 is arranged on one of the 120 train-wheels, as 20 for instance, which wheel, it will be noted, is secured to the signal-wheel shaft, and during each rotation of said wheel, said pin passes a projection 76 on the box-controller, as shown in Fig. 2. 125 Said pin however normally occupies this position opposite said projection.

When the armature is in its retracted position, as it will be while the signal is being delayed, said pin in its orbital movement 130

will engage said projection 76 and mechanically move the box-controller and armature into attracted position. This will be done during the time the notch in cam 63 is beneath the projection 61 on the prop and 5 while said prop is in its propping position, which it assumed instantly the notch passes beneath it; as the key itself, on account of retraction of the armature, was then held in closed position by said retracted armature. After the restoring pin 75 passes the projection 76 on the box-controller, said controller 10 will then be left under control of the magnet until the first tooth of the signal-wheel passes beneath the signal-key, as was the case when the box was first pulled. The period of time elapsing while the armature is thus left under control of its magnet and before the key can thereafter open the circuit is longer than any closure in a signal and if the circuit remains continuously closed during this period, it indicates that 20 no signal is then using the line, and the key is then free to begin its signal. In case the armature is not held by the non-interference magnet during the whole of this time, then it will again resume its retracted position to again lock the key during the succeeding revolution of the signal-wheel.

25 These repeated attempts to send the delayed signal will be continued for an allotted period of time, and will then cease, for eventually the box-controller will be mechanically blocked from farthest retraction so that the pin 70 will be held out of engagement with the dog 31 thereafter, whereupon the train will then engage and drive the stopping-means until the notch of the disk 36 arrives in position for reengagement of the locking-member 39, and the train will be stopped. In case the line 30 was not free of other signals or in condition to send the attempted signal up to such time then the delayed signal will not be sent.

35 For the accomplishment of these results a counting-device is provided, adapted to be moved one step for each round of the signal, or for each attempt to send a round of the signal, which, as here shown, comprises a mutilated ratchet-wheel 80, having 40 a series of teeth adapted to be successively engaged by the aforesaid pin 75, on the train-wheel 20, or by other means operated by the signaling-train on or at the end of 45 each round of the signal, to move it intermittently, and having a single long tooth 81, also adapted to be engaged by said pin 75, and having next said long tooth a void or interdental space. Said ratchet-wheel is 50 mounted loosely, for convenience, on the winding-shaft, and it has a circumferentially grooved hub 83; and a spring 84 is attached at one end to the wheel, and at the other end to a pivoted member 85, or it may 55 be to some other point. This spring is ar-

ranged to be wound upon said hub, in the groove thereof, as the ratchet-wheel is intermittently rotated, and is employed to return the ratchet-wheel to its normal position, when so permitted to act.

70 The member 85 is designed to serve as a stop to hold the ratchet-wheel in its normal position, as shown by dotted lines Fig. 2, and also as a pawl to hold the ratchet-wheel in any of its intermediate positions. 75 This member is pivoted at 86, and has a nose 100, arranged for engagement with the long tooth 81, and has a projection 89, arranged for engagement with the teeth of the ratchet-wheel. Said member 85 is movable 80 on its pivot into and out of co-active relation with the teeth of the ratchet-wheel, and normally is so held that its projection 89 is out of the path of movement of the short ratchet-teeth. To move this member 85 a 85 long slot 87, is formed in it which receives a projection on a member 88, which is secured to the shaft of the locking-member, so that upon a lifting movement of the locking-member said member 88 may be correspondingly lifted. The slot 87 in lever 85 is so shaped that when member 88 is lifted the member 86 can move into the position shown in Fig. 7, whereupon its projection 90 95 will be in position for co-action with the teeth of the ratchet-wheel, but when the locking-lever drops it will again raise lever 85. The spring 84 being attached to said member 85 serves to yieldingly hold it in engagement with the ratchet-teeth, permitting it to yield as the teeth of the ratchet-wheel pass the projection 89.

100 Thus it will be seen that the co-active relation of the components of the counting-device are controlled by the locking-member, 105 which forms a component part of the stopping-means, and the counting-device will be active during the time the signaling-train is running.

110 During the running of the train, and at the end of each round of the signal, the pin 75, will engage and move the ratchet-wheel 80 one step, and said wheel will be held by the member 85, but as soon as the stopping-means resumes its normal or stopping position and its locking-member enters the notch of the stop-wheel, the member 85 will be returned to its normal position, and having thus disengaged the ratchet-wheel 115 said ratchet-wheel is permitted to resume its normal position by the action of the spring 84.

120 In case the line is free, and the stopping-means admits of, say, four rounds of the signal being sent, the only function subserved by the counting-device will be those above described. In case, however, the line is not free and the signal is delayed, and the stopping-means is disconnected from the signaling-train, then the ratchet-wheel will be 125 successively advanced step by step for a pre- 130

determined number of rounds of the signal, say eleven rounds, when its long tooth 81 will arrive in position for engagement with the pin 75; and a pin 90, which is extended laterally from said tooth will engage the end of the box-controller, as represented in Fig. 8, and as the train continues to run the box-controller will be partially returned and thereafter held by the ratchet and pin in an intermediate position, but still out of effective field of the non-interference magnet. Such partial return movement of the box-controller is sufficient to move the pin 70 out of engaging position with the tail of the dog 31 permitting movement of said dog, so that the pin 30 will thereafter engage said dog, and thus connect the stopping-means with the train. Said stopping-means will be then continuously driven by the train, in regular manner, for the sending of the delayed signal, which, however, may or may not be sent, depending upon the condition of the circuit, but at the end of the predetermined number of attempted rounds the locking-member will enter the notch of the stop-wheel and stop the train, so that the delayed signal will not be sent.

Whether or not the delayed signal is sent it will be observed that the stopping-means will stop the train, and the counting-device is thereby caused to resume its normal position, the co-active relation of its component parts becoming disengaged. Hence will be seen that after many attempts to send a delayed signal during an allotted period of time, the signaling-train is stopped, and all of the component parts of the box caused to resume their normal positions and long before the box has exhausted its round capacity, so that the box must not only be again pulled to send its signal, but that it will have ample capacity for sending each signal when so required.

During the many attempts to automatically commence and send a delayed signal it will be noted that in case any attempt is successful, the counting-device will act accordingly, to count it out and then will be returned to normal whenever the stopping-means has been connected with the train and has been driven by the train for its full period of time, and has resumed its normal position.

Whenever the locking-lever is permitted to resume its normal position the pin 56 thereon will engage the extension 55 on the signal-key, and will restore and hold said key in its closed position so that the prop can pass beneath it to occupy a position to prevent said key opening when the box is again pulled and until the signal-wheel has been advanced to engage the key.

As here shown, the armature and box-controller have associated with them an improved form of tension so constructed that

as the armature retracts the tension rapidly increases in leverage, whereby the armature will be held in retracted position against attraction of its magnet even though the strength of the current varies considerably and increases much beyond the normal amount. Such arrangement insures correct working of the non-interference devices even under great variation of current conditions of the circuit, which variations are of advantage at time of signaling to increase speed of correct signaling. This tension device consists of an arm 102, attached to the box-controller and extended above its pivot for a considerable distance, to the upper end portion of which one end of a link 103 is loosely connected, the other end of said link being connected to one end of a spring 104, and the other end of said spring being loosely connected to an adjusting-screw 105 much below the pivot. The line of force of the tension when the armature is in attracted position is then near the pivotal point of the armature so that a small current will hold the armature attracted.

As the armature is retracted the upper end of the arm 102 carries the line of force of the spring away from said pivot and thereby rapidly increases the leverage of said spring against attraction of the magnet, tending to hold the armature retracted even when the magnet is influenced by an excessively strong current.

I claim:

1. In a signal-box, the combination of a signaling-train, stopping-means adapted to be operated by the train to stop the train at the end of a predetermined number of rounds, means to connect said stopping-means with and disconnect it from the train, and a non-interference magnet having a box-controller associated with it arranged to control said connecting-means.

2. In a signal-box, the combination of a signaling-train, stopping-means for the train, means to connect said stopping-means with and disconnect it from the train, a non-interference magnet having a box-controller associated with it arranged to disconnect said stopping-means from the train, and means operated by the train in running to move said box-controller to permit connection of said stopping-means with the train.

3. In a signal-box, the combination of a signaling-train, stopping-means for the train, means to connect said stopping-means with and disconnect it from the train, a non-interference magnet having a box-controller associated with it arranged to disconnect said stopping-means from the train, and means operated by the train in running to move said box-controller to permit connection of said stopping-means with the train at the end of each round of the signal.

4. In a signal-box, the combination of a

signaling-train, stopping-means for the train, means to connect said stopping-means with and disconnect it from the train comprising a dog, and a pin associated, respectively, with the stopping-means and the train, a non-interference magnet and box-controller associated therewith arranged to move said dog out of engaging position.

5. In a signal-box, the combination of a signaling-train, stopping-means for the train, means to connect said stopping-means with and disconnect it from the train comprising a dog, and a pin associated, respectively, with the stopping-means and the train, a non-interference magnet and box-controller associated therewith arranged to move said dog out of engaging position, and means controlled by the train in running to return said dog to engaging position.

10. In a signal-box, the combination of a signaling-train, stopping-means for the train, means to connect said stopping-means with and disconnect it from the train comprising a dog, and a pin associated, respectively, with the stopping-means and the train, a non-interference magnet and box-controller associated therewith arranged to move said dog out of engaging position, and means controlled by the train in running to permit return of said dog to engaging position at the end of each round of the signal.

15. In a signal-box, the combination of a signaling-train, stopping-means for the train adapted to be operated by the train and to stop the same at the end of a predetermined number of rounds of the signal, connecting-means adapted to connect the stopping-means with and disconnect it from the train, and a non-interference magnet

20. having a box-controller associated with it arranged to control said connecting-means.

25. In a signal-box, the combination of a signaling-train, stopping-means for the train adapted to be operated by the train and to stop the same at the end of a predetermined number of rounds of the signal, connecting-means adapted to connect the stopping-means with and disconnect it from the train, and a non-interference magnet

30. having a box-controller associated with it arranged to control said connecting-means, and means operated by the train in running arranged to permit operation of the connecting-means to connect the stopping-means with the train at the end of each round of the signal.

35. In a signal-box, the combination of a signaling-train, stopping-means for the train, means to connect said stopping-means with and disconnect it from the train comprising a dog borne by a rotating-member associated with the stopping-means, and a pin borne by one of the train-wheels, a non-interference magnet and box-controller asso-

40. ciated therewith arranged to engage said dog to cause said dog to move out of engaging position and permit the pin to pass by it.

45. In a signal-box, the combination of a signaling-train, stopping-means for the train, means to connect said stopping-means with and disconnect it from the train comprising a dog borne by a rotating-member associated with the stopping-means, and a pin borne by one of the train-wheels, a non-interference magnet and box-controller associated therewith arranged to move said dog out of engaging position and permit the pin to pass by it, and means controlled by the train in running for moving the box-controller to admit of the return movement of the dog to engaging position.

50. In a signal-box, the combination of a signaling-train, stopping-means for the train, means to connect said stopping-means with and disconnect it from the train comprising a dog borne by a rotating-member associated with the stopping-means, and a pin borne by one of the train-wheels, a non-interference magnet and box-controller associated therewith arranged to move said dog out of engaging position and permit the pin to pass by it, and means operated by the train in running for moving the box-controller to permit return movement of the dog to engaging position.

55. In a signal-box, the combination of a signaling-train, stopping-means for the train, connecting-means for connecting said stopping-means with and disconnecting it from the train, a non-interference magnet, a controlling-lever arranged to be controlled by the non-interference magnet adapted to control said connecting-means which when said magnet is energized permits connection of the stopping-means with the train, and when deenergized permits disconnection of the stopping-means from the train.

60. In a signal-box, the combination of a signaling-train, stopping-means for the train, connecting-means for connecting said stopping-means with and disconnecting it from the train, a non-interference magnet, a controlling-lever arranged to be controlled by the non-interference magnet adapted to control said connecting-means which when said magnet is energized permits connection of the stopping-means with the train, and when deenergized permits disconnection of the stopping-means from the train, and means controlled by the train in running for moving said controlling-lever into attracted position at the end of each round of the signal.

65. In a signal-box, the combination of a signaling-train, stopping-means for the train, connecting-means for connecting said stopping-means with and disconnecting it from the train, a non-interference mag-

- net, a controlling-lever for said connecting-means arranged to be controlled by said magnet, means operated by the train in running for holding said controlling-lever out of engagement with the connecting-means at the beginning of a round of the signal, and releasing it during a round of the signal permitting it to operate and disconnect the stopping-means from the train.
- 10 15. In a signal-box, the combination of a signaling-train, a signal-key, stopping-means for the train, connecting-means for connecting said stopping-means with and disconnecting it from the train, a non-interference magnet, a box-controller associated therewith, which, when in one position holds the signal-key in closed position, and when in another position permits movement of said signal-key, said box-controller being also arranged to operate the connecting-means to disconnect the stopping-means from the train, while holding the signal-key in closed position.
- 15 20. In a signal-box, the combination of a signaling-train, a signal-key, stopping-means adapted to be operated by the train to stop the train at the end of a predetermined number of rounds, means for connecting said stopping-means with and disconnecting it from the train, and signal delaying-means consisting of a non-interference magnet, armature therefor, and box-controller connected with said armature and arranged to control the connecting-means for said stopping-means, and also to control the signal-key.
- 20 25. In a signal-box, the combination of a signaling-train, stopping-means therefor, signal delaying-means associated with the train including a non-interference magnet, and a round counting-device adapted to be operated by the train and to be restored by the stopping-means.
- 25 30. In a signal-box, the combination of a signaling-train, stopping-means therefor, signal delaying-means associated with the train including a non interference magnet, and a round counting-device adapted to be operated intermittently by the train and to be restored by the stopping-means.
- 30 35. In a signal-box, the combination of a signaling-train, stopping-means therefor, signal delaying-means associated with the train including a non-interference magnet, and a round counting-device adapted to be operated intermittently by a pin on one of the train-wheels and to be restored by the stopping-means.
- 35 40. In a signal-box, the combination of a signaling-train, stopping-means therefor, signal delaying-means associated with the train including a non-interference magnet, and a toothed wheel arranged to be operated step by step by a pin on one of the train-wheels for counting the rounds of the

signal, a pawl for said toothed wheel adapted for operation by the stopping-means to permit return of said wheel.

40 45. In a signal-box, the combination of a signaling-train, stopping-means therefor, signal delaying-means associated with the train including a non-interference magnet, a round counting-device adapted to be operated by the signaling-train to count the number of rounds, one of the components of which is connected with the stopping-means whereby it is restored by the stopping-means.

50 55. In a signal-box, the combination of a signaling-train, stopping-means therefor, means for connecting the stopping means with and disconnecting it from the train, signal delaying-means associated with the train including a non-interference magnet, a round counting-device controlling the connecting means for the stopping-means which is adapted to be operated by the signaling-train and controlled by the stopping means.

60 65. In a signal-box, the combination of a signaling-train, train-driven stopping-means therefor, signal delaying-means associated with the train including a non-interference magnet, a round counting-device arranged to control the operation of the stopping-means which is adapted to be operated by the signaling-train, the component parts of said device being movable into and out of co-active relation by the stopping-means.

70 75. In a signal-box, the combination of a signaling-train, signal delaying-means associated with the train including a non-interference magnet, a round counting-device adapted to be operated by the train to move the signal delaying-means into position to be subsequently restored to normal, so that a delayed signal may not be sent.

80 85. In a signal-box, the combination of a signaling-train, signal delaying-means associated with the train including a non-interference magnet, a round counting-device adapted to be operated intermittently by the train for a predetermined number of rounds, and then to move the signal delaying-means into position to be subsequently restored to normal, so that a delayed signal may not be sent.

90 95. In a signal-box, the combination of a signaling-train, stopping-means therefor, signal delaying-means associated with the train including a non-interference magnet, a round counting-device adapted to be operated by the train, and to move the delaying-means to control the operation of the stopping-means.

100 105. In a signal-box, the combination of a signaling-train, stopping-means therefor, signal delaying-means associated with the train including a non-interference magnet, a round counting-device adapted to be operated intermittently by the train for a pre-

determined number of rounds, said device having means arranged to move the signal delaying-means at the end of said predetermined number of rounds to control the operation of the stopping-means.

5 28. In a signal-box, the combination of a signaling - train, a signal key, signal delaying - means associated therewith having means for holding the signal-key in closed position, a round counting device adapted to be operated by the train to move the signal delaying-means into position to control the stopping of the train while continuing to hold the signal-key in closed position.

10 29. In a signal-box, the combination of a signaling - train, a signal key, stopping-means for the train, signal delaying-means associated with the train arranged to disconnect the stopping-means therefrom, and to hold the signal-key in closed position, and a round counting-device adapted to be operated by the train and to move the delaying-means sufficiently to connect the stopping-means with the train, but not to permit movement of the signal-key into open position.

15 30. In a signal-box, the combination of a signaling - train, a signal key, stopping-means for the train, signal delaying-means associated with the train arranged to disconnect the stopping-means therefrom and to hold the signal-key in closed position, and a round counting-device adapted to be operated intermittently by the train in correspondence with the rounds of the signal and after a predetermined number of rounds to move the delaying-means sufficiently to connect the stopping-means with the train, but not to permit movement of the signal-key into open position.

20 31. In a signal-box, the combination of a signaling - train, a signal key, stopping-means for the train, signal delaying-means associated with the train including a non-interference magnet arranged to disconnect the stopping-means therefrom and to hold the signal-key in closed position, and a round counting-device adapted to be operated intermittently by the train in correspondence with the rounds of the signal and after a predetermined number of rounds to move the delaying-means sufficiently to connect the stopping-means with the train, and place said delaying-means under the influence of its non-interference magnet.

25 32. In a signal-box, the combination of a signaling - train, stopping-means therefor, signal delaying-means associated with the train including a non-interference magnet, a round counting-device adapted to be operated by the train and to move the delaying-means to control the operation of the stopping-means, said counting-device being subsequently restored by the stopping-means.

33. In a signal-box, the combination of a signaling-train, stopping-means for the train, signal delaying-means associated with the train including a box-controller arranged to disconnect the stopping-means from the train, a round counting-device adapted to be operated by the train for a predetermined number of rounds, and then to move the box-controller into position to permit connection of the stopping-means with the train. 70

34. In a signal-box, the combination of a signaling-train, stopping-means for the train, signal delaying-means associated with the train including a box-controller arranged to disconnect the stopping-means from the train, a round counting-device adapted to be operated by the train for a predetermined number of rounds, and then to move the box-controller into position to permit connection of the stopping-means with the train, said 80 counting-device being subsequently restored by said stopping-means.

35. In a signal-box, the combination of a signaling-train, stopping-means for the train, signal delaying-means associated with the train including a box-controller arranged to disconnect the stopping-means from the train, a round counting-device adapted to be operated by the train for a predetermined number of rounds, said device having means arranged to move the box-controller into position to permit connection of the stopping-means with the train, and said device having one of its components associated with the stopping-means whereby 90 it is rendered active and restored thereby. 95

36. In a signal-box, the combination of a signaling-train, a signal key, stopping-means for the train, signal delaying-means associated with the train including a box-controller arranged to disconnect the stopping-means from the train, and to hold the signal-key in closed position, a round counting-device adapted to be operated by the train for a predetermined number of rounds, 105 and then to move the box-controller into position to permit connection of the stopping-means with the train, without disengaging the signal-key. 110

37. In a signal-box, the combination of a signaling-train, stopping-means for the train, means to connect said stopping-means with and disconnect it from the train, a non-interference magnet and box-controller controlled by it arranged to operate said connecting-means to disconnect the stopping-means and delay the sending of the signal, and a round counting-device adapted to be operated by the signal-train to move said box-controller into position to permit connection of the stopping-means with the train. 115 120

38. In a signal-box, the combination of a signaling-train, a signal key, stopping-means for the train, means to connect said 130

- stopping-means with and disconnect it from the train, a non-interference magnet and box-controller controlled by it arranged to operate said connecting means to disconnect the stopping-means and to hold the signal-key in closed position thus delaying the sending of the signal, and a round counting-device adapted to be operated by the signaling-train to move said box-controller into position to permit connection of the stopping-means with the train, without disengaging the signal-key.
39. In a signal-box, the combination of a signaling-train, a signal key, stopping-means for the train, means to connect said stopping-means with and disconnect it from the train, a non-interference magnet and box-controller controlled by it arranged to operate said connecting means to disconnect the stopping-means and hold the signal-key in closed position thus delaying the sending of the signal, and a round counting-device adapted to be operated by the signal-train for a predetermined number of rounds, and then to move said box-controller into position to be subsequently placed under the control of the non-interference magnet so that a delayed signal may be sent, and to permit connection of the stopping-means with the train without disengaging the signal-key.
40. In a signal-box, the combination of a signaling-train, a signal key, stopping-means for the train, means to connect said stopping-means with and disconnect it from the train, a non-interference magnet and box-controller controlled by it arranged to operate said connecting means to disconnect the stopping-means and hold the signal-key in closed position thus delaying the sending of the signal, and a round counting-device

adapted to be operated by the signal-train for a predetermined number of rounds, and then to move said box-controller into position to be subsequently placed under the control of the non-interference magnet so that a delayed signal may be sent, and to permit connection of the stopping-means with the train, without disengaging the signal-key, said counting-device being subsequently restored by the stopping-means.

41. In a signal-box, a signaling-train having a main spring and a winding-shaft to which one end of said spring is connected, a toothed gear secured to the winding-shaft having a laterally extended pin, a pinion 55 engaged by said gear, and a stopping-member arranged to rotate with said pinion having a projection which repeatedly enters the orbital path of the pin as the gear rotates and after several revolutions thereof engages the pin.

42. In a non-interference signal-box, including a non-interference magnet, armature and box-controller, a tension-device connected to the box-controller consisting of an arm attached thereto and rising therefrom radially with respect to its pivot, a link loosely connected to the extremity of said arm, and a spring connecting said link with an adjusting screw, whereby the force exerted by the tension device will rapidly increase as the armature moves from its attracted to its retracted position.

In testimony whereof, I have signed my name to this specification, in the presence 75 of two subscribing witnesses.

FREDERICK W. COLE.
